UNITED STATES PATENT OFFICE

FRANZ KRUCKENBERG, OF HEIDELBERG, GERMANY

METHOD OF OBTAINING ENTRY AND EXIT TIMES OF ANY DESIRED LENGTH IN RAILWAYS WITH VERY CLOSE TRAIN SEQUENCE

Application filed March 15, 1928, Serial No. 261,889, and in Germany June 6, 1927.

If the load capacity of rapid transport railways must be made as high as possible, this cannot be done only by increasing the speed and arranging the signalling so that the time 5 intervals between trains are made as small as possible. Care must be rather taken, that the station rhythm corresponds to that of the line as determined by the above mentioned factors. Otherwise it happens, as can be observed in the rapid transport town-railways 10 in many large towns, that just at the times of greatest traffic the load capacity of the whole railway falls below the normal value, owing to the fact, that passenger loading and unloading in the stations increase the intervals 15 at which the trains can follow one another.

Two extreme cases can be observed in the railway vehicles at present in use. On the one hand there is the arrangement used in 20 long distance-trains, in which the passengers must enter or leave each vehicle by a single door at each end; on the other hand the vehicles of switch-backs, in which each individual passenger can pass directly from the platform 25 to his place.

Remembering how inconvenient is the method of mounting by the steep steps in long distance-trains, it is clear that this is exactly that, what should not be done in an effective 30 rapid transport railway. On the other hand a number of conditions render impossible the simple solution of leaving the sides open as for example in the so called "summer cars" of street tramways. Each door opening renders 35 more difficult the attempt to make the whole vehicle-body as light and stable as possible, by constructing it as a beam (with the floor as the lower flange, the roof as the upper flange and the walls as the web).

40 An embodiment of the invention is illustrated in the accompanying drawings in which

Fig. 1 is a plan view showing a series of vehicles and the associated loading and unloading platforms;

Fig. 2 is a diagrammatic representation of the distribution of passengers on the platform and vehicle;

Figs. 3 and 4 are perspective views of the 50 opposite ends of a loading platform.

In order to ensure a rapid change of passengers in spite of small door openings, the stream of passengers must be able to pass rapidly and in one direction.

For this purpose the stations are provided 55 both with inner and outer platforms. The vehicles 10 have, as shown in Figure 1 of the accompanying drawings for example at the front a door 11 only on the left, which serves solely as an exit and opens for example on 60 to the inner platform 12, and at the rear a door 13 on the right which serves only as an entrance from the outer platform 14, or vice versa. Shortly before the train stops the 65 passengers will take their places near the door 11. The setting in motion of the stream of passengers from rear to front can be encouraged by arranging the front door 11 to open automatically before the rear door 13.

With an efficient signalling system a very 70 short train sequence interval is obtainable in rapid transport railways designed for mass traffic. If this short interval is to be maintained, the loading and unloading in the station must take place in the same period. The 75 unloading and loading procedure in a through-way station, apart from small additional periods, consists mostly of actual standing time and stopping and starting time within the station section. The stopping and starting time 80 in the station section with the same vehicle is constant for all train sequence intervals, therefore the shorter the train intervals, the shorter are the actual standing times for entry and exit. As the train intervals are 85 decreased, the standing time at a station may therefore become so short as to be insufficient for the change of passengers.

According to the invention as long a time 90 for entry and exit of passengers as desired can be obtained. For this it is necessary for the individual vehicles to move slowly through the stations. The lowest speed with which the vehicles can pass in this way 95 through the stations is proportional to the length of the vehicles and inversely proportional to the sequence interval. With the vehicles rolling slowly through the station it is particularly easy for the front exit doors opening on to the middle platform to be 100

opened before the rear entry doors. This can be effected as soon as the door reaches the beginning of the platform. The vehicle commences to empty forwards. The rear door only reaches the beginning of the outer platform some time later, so that entry of passengers only commences when the exit stream where possible has already finished.

When sufficient time for the transfer of passengers from the platform to the vehicle and vice versa has been achieved by the above described arrangement, and a flow in one direction has been attained, by arranging the middle platform for leaving passengers and the outer platform for entering passengers, there is still something lacking in that the traffic stream on the platforms is itself not uniform and continuous. This can be achieved by the passengers being conducted to the vehicles slowly passing through the stations by the aid of moving stairways (escalators) and travelling platforms. These moving stairways and platforms must be so dimensioned for constant speeds that they can carry the necessary number of passengers for filling or emptying. At the same time the vehicles and moving platform do not need to have the same forward speeds. From among the many possible combinations an example based on an ideal motion diagram is described below. Assuming for example that in rapid transport railways the largest individual vehicle or train is 60 metres long, that there are 8 passengers per metre length, and that the maximum speed, breaking times and signalling system involve a time interval of 60 seconds between the individual vehicles or trains, then 480 passengers pass through any given cross section of the line in 60 secs. The transport capacity in respect of number per unit time is the same if 8 passengers pass through a given cross section every second. This means that in the rapid transport railway under consideration, a traffic stream can be assumed in which columns of 8 at 1 metre apart move forward at a speed of 1 m./sec.

In Figure 2 of the accompanying drawings is shown a movement diagram for a station. The small circles indicate passengers. They walk in eights on the section marked 15 with a speed of 1 metre/sec. (3.6 km./hr.) at distances of 1 metre. At 16 they reach for example the steps of a moving stairway which moves for example at a speed of 0.5 m./sec. On the stairway section 17 the passengers are crowded together so far as they do not walk forward on the steps in the manner experience shows to be usual.

The moving stairway changes to a moving platform at 18; 20 are rapid transport railway vehicles which pass through the station at a speed of 1 m./sec. The speed difference between the moving platform and the vehicles is consequently 0.5 m./sec. which must

be made up by the passengers moving on the platform if they do not prefer to stand still in order to enter at one of the next doors. In the example given 8 persons per second must always pass any given point on the traffic path, consequently through the boundary line between 19 and 20. If the vehicles have few doors the section 19 will be long and so much smaller as more doors are provided.

In order to achieve the result aimed at by the invention, it is naturally not essential to adopt the arrangement described in the above ideal example. If the lowest speed at which the vehicles close together must pass through the station is too high, several moving platforms with different speeds can be provided which permit a passage from the stationary platform to the moving vehicles. It may also be in the interest of safe and rapid passage into the vehicles for the moving platform next to the vehicles to move at the same speed as the vehicles. If effective traffic discipline can be maintained so that the passengers do not themselves move along the moving platform but remain standing until they are opposite a door into which they can pass—this applies to the case when the vehicles move at a different speed from the platform—then the arrangement of separate platforms can be dispensed with and the entry and exit take place with a single platform.

If the moving platform is arranged to change into a moving stairway at the ends, a further result is obtained. The passengers will then be automatically prevented from reaching the trains and being injured at particular danger points, as exist for example in ordinary railways at the platform ends. The passengers will be carried away from the doors by the moving platform sinking beneath them as a stairway. For railways in which the departure of the trains from the stations is dependent on the closing of automatically operated doors, this arrangement is particularly advantageous since the incessant re-opening of the half closed doors will be automatically prevented.

In Figures 3 and 4 the beginning and end of a platform lay-out as described is shown in perspective.

By means of the moving stairway 17 (Figure 3) the passengers reach the moving platform 19. Anyone fearing the moving stairway can instead use the staircase 21, first reaching the stationary platform 22, and stepping from this on to the moving platform 19. The moving platform at the other end (Figure 4) again changes over to a moving stairway 23. When during the passage of the vehicle 20 the door 24 has reached the end of the moving platform 19, the removal of the passengers from the door takes place automatically. When the door has reached the position shown in dotted lines in Figure

4, no passenger can remain at a doorway any longer since the floor on which he previously stood has descended by the height of a man. The only course left to the passenger, 5 who hitherto would not willingly leave the door opening, is to ascend the fixed stairway 25, to return along the fixed platform 22 to the commencing end of the moving platform and to try again to enter a vehicle.

10 Having now particularly described and ascertained the nature of my said invention and in what manner the same is to be performed, I declare that what I claim is:

15 1. A transportation system of the type in which a moving platform travels parallel to the right of way to provide a station, characterized by the fact that said platform terminates, at the respective ends thereof, in moving stairways.

20 2. The invention as set forth in claim 1, wherein said stairways are positioned, with reference to vehicles moving on said roadway, to move passengers away from the doorways of said vehicles.

25 3. In a transportation system, the combination with a moving platform serving as a loading station, of a moving stairway at each end of said moving platform, said stairways operating between the level of said moving platform and a lower level, whereby 30 prospective passengers are automatically moved away from the vehicle entrances at the exit end of said station.

35 4. The invention as set forth in claim 3, in combination with stationary stairs and a stationary platform at the side of said moving platform remote from the right of way, said stationary and moving stairs and platforms, respectively, being aligned to constitute, in effect, a single station structure in 40 which the sections adjacent the right of way travel in the direction of vehicle travel.

In testimony whereof I have affixed my signature.
